(57) **CLAIM**

The ornamental design for a coffee grinder as shown and described.

DESCRIPTION

Reproduction 1.1 is a first perspective view of a coffee grinder showing my new design;

Reproduction 1.2 is a second perspective view thereof;

Reproduction 1.3 is a right side view thereof;

Reproduction 1.4 is a front view thereof;

Reproduction 1.5 is a left side view thereof;

Reproduction 1.6 is a back view thereof; and

Reproduction 1.7 is a top view thereof.

The broken lines in the reproductions are for showing portions of the coffee grinder that form no part of the claimed design.

1 Claim, 7 Drawing Sheets
